RAILWAY SIGNALING

Ralph R. Kemmerer, Swissvale, Pa., assignor to
 The Union Switch & Signal Company, Swiss-
 vale, Pa., a corporation of Pennsylvania

Application March 6, 1936, Serial No. 67,495

33 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of four sections in the rear of an occupied section. Each distinctive control is effective to cause a corresponding aspect of the associated wayside signal whereby there is produced a four-block, five-indication, system of signaling.

10 Another feature of my invention is the provision of novel and improved apparatus for establishing a distinctive control for each of three sections in the rear of an occupied section for controlling the associated wayside signal whereby there is produced a three-block, four-indication, system of signaling.

15 I will describe several forms of apparatus each embodying my invention, and will then point out the novel features thereof in claims.

20 In the accompanying drawings, Figs. 1A, 1B, and 1C are diagrammatic views which, when placed end to end in the order named, illustrate one form of apparatus embodying my invention for providing four-block, five-indication, signaling. Figs. 2A and 2B are diagrammatic views which, when placed end to end in the order named, illustrate another form of apparatus embodying my invention for providing three-block, four-indication signaling. Figs. 3, 4, and 5 are diagrammatic views each illustrating a modification of a portion of the apparatus shown in Fig. 2A and each also embodying my invention.

25 30 Similar reference characters refer to similar parts in each of the several views.

35 Referring first to Figs. 1A, 1B, and 1C, the reference characters 17 and 18 designate the rails of a stretch of railway track along which traffic normally moves in the direction indicated by the arrows. These rails are divided by insulated joints 19 into a plurality of track sections or blocks V—W, W—X, X—Y, and Y—Z.

40 45 As here shown, each track section is divided by insulated joints into at least two subsections 1T, 2T, 3T, 4T, etc. Each subsection is provided with a track circuit which includes a track battery 20 connected across the rails at one end of the subsection and a track relay, designated by the reference character TR with a prefix the same as the numerical prefix in the reference character for the associated subsection, connected across the rails at the other end of the subsection.

5 To govern the passage of trains through the stretch, a wayside signal designated by a suitable distinguishing reference character is located at the entrance to each track section. Each of these signals includes an upper unit U and a lower unit L. These units may take any one of several forms of signal mechanism such as searchlight, semaphore, color light, or position light. As here shown, each unit U and each unit L is a searchlight signal mechanism substantially as described and claimed in United States Letters Patent No. 1,864,224, granted June 21, 1932, to W. B. Wells, for Light signals.

10 15 For the purpose of this application, it is deemed sufficient to describe but briefly these signals. The upper unit U of signal 10, for example, includes a pivotally mounted rotor 21 controlled by a permanent magnet (not shown) and by an operating winding 22. Energization of operating winding 22 by current of one polarity causes rotor 21 to be rotated in one direction, moving the signal to the clear indication position; energization of operating winding 22 by current of the opposite polarity causes rotor 21 to be rotated in the opposite direction to move the signal to the caution indication position; while deenergization of operating winding 22 permits rotor 21 to be returned by gravity to an intermediate position, which is the stop indication position.

20 25 30 Associated with rotor 21 is a lamp 10UE. As pointed out in detail in the aforementioned patent, when rotor 21 is rotated to the clear position, a green colored filter G is moved in front of lamp 10UE so that a green signal light will be displayed when the lamp is lighted. When rotor 21 is rotated to the caution indication position, a yellow colored filter Y is moved in front of lamp 10UE so that a yellow signal light is displayed when the lamp is lighted. In a like manner, the positioning of rotor 21 in the intermediate position moves a red colored filter R in front of lamp 10UE so that a red signal light is displayed whenever the lamp is lighted.

35 40 45 Each of the searchlight mechanisms U and L with their associated lamps UE and LE, for each of the signals, functions in a manner similar to that just described for the mechanism U and lamp UE of signal 10.

45 50 Each section is provided with a line circuit including a pair of line wires each of which includes a front contact of each of the associated track relays.

55 For controlling the signals, each section is provided with a polarized direct current relay

of the retained neutral type having a slow pick-up characteristic and designated by the reference character H with a prefix the same as the reference character of the associated signal.

5 Each relay H includes an operating winding 23 and a retaining winding 24 which is inductively coupled with the operating winding and is effective for retaining the neutral armature in its picked up condition during pole-changing periods. Each operating winding 23 is directly connected to the associated line circuit and each retaining winding is controlled over a front contact of the track relay for the rear subsection of the associated track section. For example, the 10 retaining winding 24 of relay 10H is controlled over front contact 25 of track relay 1TR. As will be explained more in detail hereinafter, this feature insures a quick release of the relay 10H when a train enters section 1T so that a momentary improper energization of the line circuit to the rear of location V is avoided.

15

20

For also controlling the signals, each section is provided with a direct current neutral relay designated by the reference character J with a prefix the same as the reference character of the associated signal. Each relay J is connected to the associated line circuit by a resistor, a transformer, and an asymmetric unit designated by the reference characters F, M, and Q, respectively, each with a prefix the same as the reference character of the associated signal.

The relatively high impedance of the relays H prevents the flow of alternating current in these relays and the transformers M prevent the flow of direct current in the relays J. The resistors F prevent excessive flow of direct current in the primary windings of the transformers M.

Each section is provided with a suitable source of direct current, here shown as a battery 9, the terminals of which are designated by the reference characters B and C, and with a suitable source of alternating current the terminals of which are designated by the reference characters BX and CX.

45 Each section is provided with a transformer N having a primary winding 26 directly connected to the alternating current terminals BX and CX and including a secondary winding 27.

As will be explained more in detail hereinafter, the relays H and J connect the secondary windings 27 and the direct current terminals B and C with the line circuit for the section next in rear in such a manner that the line circuit is supplied with direct current only of normal polarity or with direct current only of reverse polarity or with alternating current simultaneously with direct current of normal or reverse polarity.

For controlling the associated lamps UE and LE, each section is provided with an approach lighting relay designated by the reference character ER with a prefix the same as the reference character of the associated signal. Each relay ER is connected in series with the line circuit for the section next in rear so that these relays are normally energized and become deenergized only when the section next in rear is occupied by a train. The lamps UE and LE are controlled over a back contact of the associated relay ER. For example, the lamps 10LE and 10UE are controlled by circuits each of which includes back contact 28 of relay 10ER so that these lamps are lighted only when relay 10ER is released, that is, when the section next in rear of location V is occupied.

Each lamp UE and LE is controlled in a similar manner by the associated relay ER for the remaining signals.

The impedance of the relays ER is of such value as to offer substantial resistance to the passage of alternating current. In order to bypass the greater portion of the alternating current, each relay ER is provided with a resistor 29 connected across the relay winding. The value of resistors 29 is so chosen that sufficient direct current will flow through the relays ER to maintain these relays energized when the line circuit is closed.

The relays H and J control the signal in the following manner: When relay H is deenergized (see signal 14), the operating windings 22 of both upper and lower units U and L are in the deenergized condition so that when lamps 14UE and 14LE are lighted, the signal will display a red light above a red light to indicate "stop". When relay H is energized in the reverse direction and relay J is deenergized (see signal 13), operating winding 22 of upper unit U of that signal is energized in the reverse direction by a circuit which passes from terminal B through front contact 30 of relay 13H, back point of contact 31 of relay 13J, operating winding 22, and back point of contact 32 of relay J to terminal C; and operating winding 22 of lower unit L of that signal remains deenergized, so that, when lamps 13UE and 13LE are lighted, the signal will display a red light above a red light to indicate "stop".

play a yellow light above a red light to indicate "approach next signal prepared to stop". When relay H is energized in the normal direction and relay J is deenergized (see signal 12), operating winding 22 of upper unit U of that signal is energized in the reverse direction over a circuit which passes from terminal B through front contact 33 of relay 12H, back point of contact 34 of relay 12J, operating winding 22, and back point of contact 35 of relay 12J to terminal C; and operating winding 22 of the lower unit L of that signal is energized in the reverse direction over a circuit which passes from terminal B through front contact 33 of relay 12H, normal polar contact 36-37 of relay 12H, back point of contact 38 of relay 12J, operating winding 22, and back point of contact 39 of relay 12J to terminal C so that, when lamps 12UE and 12LE are lighted, the signal will display a yellow light above a yellow light to indicate "proceed at medium speed". When relay H is energized in the reverse direction and relay J is energized (see 40 45 50

signal 11), operating winding 22 of upper unit U of that signal is energized in the reverse direction over a circuit which passes from terminal B through front contact 40 of relay 11H, reverse polar contact 41—42 of relay 11H, front point of contact 43 of relay 11J, operating winding 22, front contact 44 of relay 11J, and reverse polar contact 45—46 of relay 11H, to terminal C; and operating winding 22 of lower unit L of that signal is energized in the normal direction over a circuit which passes from terminal B through front contact 40 of relay 11H, front point of contact 47 of relay 11J, operating winding 22, and front point of contact 48 of relay 11J to terminal C so that, when lamps 11UE and 11LE are lighted, the signal will display a yellow light above a green light to indicate "approach next signal at medium speed". When the relay H is energized in the normal direction and relay J is energized (see signal 10), operating winding 22 of upper unit U of that signal is energized in the normal direction over a circuit which passes 75

from terminal B through front contact 49 of relay 10H, normal polar contact 50-45 of relay 10H, front point of contact 51 of relay 10J, operating winding 22, front point of contact 52 of relay 10J, and normal polar contact 42-53 of relay 10H to terminal C; and operating winding 22 of lower unit L of that signal is energized in the normal direction over a circuit identical to that described for unit L of signal 11, so that, when lamps 10UE and 10LE are lighted, the signal will display a green light above a green light to indicate "proceed at normal speed".

As shown in the drawings, the section immediately to the right of point Z is occupied by a train K so that the line circuit for the control of relays 14H and 14J is opened with the result that both relays 14H and 14J are deenergized. Since relay 14H is deenergized, relay 13H is energized in the reverse direction over a circuit which passes from terminal B of battery 9 at signal 14, through resistor 29 and relay 14ER in multiple, back point of contact 54 of relay 14H, front contact 55 of relay 8TR, front contact 56 of relay 7TR, operating winding 23, front contact 57 of relay 7TR, front contact 58 of relay 8TR, and back point of contact 59 of relay 14H to terminal C.

Since relay 13H is energized in the reverse direction and relay 13J is deenergized, relay 12H is energized in the normal direction over a circuit which passes from terminal B of battery 9 at signal 13, through resistor 29 and relay 13ER in multiple, reverse polar contact 60-61 of relay 13H, back point of contact 62 of relay 13J, front point of contact 63 of relay 13H, front contact 64 of relay 6TR, front contact 65 of relay 5TR, operating winding 23, front contact 66 of relay 5TR, front contact 67 of relay 6TR, front point of contact 68 of relay 13H, back point of contact 69 of relay 13J, and reverse polar contact 70-71 of relay 13H to terminal C.

Since relay 12H is energized in the normal direction and relay 12J is deenergized, relay 11H is energized in the reverse direction over a circuit which passes from terminal B of battery 9 at signal 12, through resistor 29 and relay 12ER in multiple, normal polar contact 73-74 of relay 12H, back point of contact 75 of relay 12J, front point of contact 76 of relay 12H, front contact 77 of relay 4TR, front contact 78 of relay 3TR, operating winding 23, front contact 79 of relay 3TR, front contact 80 of relay 4TR, front point of contact 81 of relay 12H, back point of contact 82 of relay 12J, normal polar contact 61-83 of relay 12H, and secondary winding 27 of transformer 12N to terminal C; and primary winding 84 of transformer 11M is energized by a circuit which passes from one terminal of secondary winding 27 of transformer 12N through battery 9 at signal 11 and thence over the same circuit, excluding operating winding 23 of relay 11H but including resistor 11F, as just traced for relay 11H and back to the other terminal of secondary 23. When primary winding 84 of transformer 11M is energized, current is induced in the secondary winding 86 so that relay 11J is energized through asymmetric unit 11Q.

Since both relay 11H and relay 11J are energized, relay 10H is energized in the normal direction over a circuit which passes from terminal B of battery 9 at signal 11, through resistor 29 and relay 11ER in multiple, front point of contact 87 of relay 11J, front point of contact 88 of relay 11H, front contact 89 of relay 2TR, front contact 90 of relay 1TR, operating winding 23,

front contact 91 of relay 1TR, front contact 92 of relay 2TR, front point of contact 93 of relay 11H, front point of contact 94 of relay 11J, and secondary winding 27 of transformer 11N to terminal C; and primary winding 84 of transformer 10M is energized by a circuit which passes from one terminal of secondary winding 27 of transformer 11N through battery 9 at signal 11, and thence over the same path, excluding operating winding 23 of relay 10H but including resistor 10F, and thence back to the other terminal of secondary 27 of transformer 11N. Since primary winding 84 of transformer 10M is energized, current is induced in secondary 86 of transformer 10M so that relay 10J is energized through asymmetric unit 10Q.

Since both relays 10H and 10J are energized, the line circuit for the section next in rear of section V-W is energized by alternating current simultaneously with direct current of normal polarity so that the signal (not shown) in the rear is caused to assume its normal proceed position.

The retained neutral feature of the polarized relays H prevents tumble-down of the signal control relays to the rear. For example, when the train K vacates the section to the right of location Z so that the relay 11H is supplied with current of normal polarity to cause signal 11 to assume the normal proceed indication, the front points of neutral contacts 88 and 93 do not become opened during this pole-changing period so that the energy supplied to the line circuit for the section V-W is not disturbed. Consequently, the relay 10H and each succeeding corresponding relay to the rear remains energized.

The retaining winding 24 of each relay H is closed over a front contact of the rear track relay of the associated section so that the relays H will be comparatively quick releasing when a train is passing from a forward subsection of one track section to a rear subsection of an adjacent track section. This is done in order to avoid the signal in the rear from momentarily assuming an improper proceed position when a fast moving light engine passes from one section into another section. For example, assume that a light engine passes from subsection 2T into subsection 3T at such a speed that track relay 2TR becomes energized before track relay 3TR becomes deenergized. Under this condition, the line circuit for section V-W would be closed so that relay 10H would be energized by current of normal polarity until such time as relay 11H becomes released. Relay 10H, however, having a slow pickup characteristic does not respond immediately to such energization. In the meantime track relay 3TR will become released so that the opening of its front contact 25 will in turn open the retaining winding 24 of relay 11H so that this relay will release before relay 10H has had time to become energized. Signal 10, therefore, remains in a condition to display the "stop" indication until such time as the line circuit for the control of that signal is supplied with direct current energy in the reverse direction. Consequently, signal 10 is prevented from momentarily assuming a position to display a normal proceed indication to a following train which may be occupying the section immediately in rear of the location V.

Each of the relays H functions in a similar manner to prevent tumble-down of the signal circuits to the rear and to prevent momentary improper indications under high speed light en-

gine movements, as explained and described for signals 10 and 11.

To sum up thus far, each signal is controlled by a direct current polarized signal control relay and by a direct current neutral signal control relay. The polarized relay is directly connected to a line circuit and the neutral relay is connected to the line circuit through a transformer and asymmetric unit so that the neutral relay will be energized only when the line circuit is supplied with alternating current. The line circuit is controlled by the track relays of the section with which the signal is associated and by the signal control relays for the signal next in advance. When the polarized relay is deenergized, the associated signal is in the condition to indicate "stop" and the line circuit to the rear is supplied with direct current only of reverse polarity. When the polarized relay alone is energized in the reverse direction, the associated signal is in condition to indicate "prepare to stop at next signal" and the line circuit to the rear is supplied with direct current only of normal polarity. When the polarized relay alone is energized in the normal direction, the associated signal is in condition to indicate "proceed at medium speed" and the line circuit to the rear is supplied with alternating current as well as with direct current of reverse polarity. When the polarized relay is energized in the reverse direction and the neutral relay also is energized, the associated signal is in condition to indicate "approach next signal at medium speed" and the line circuit to the rear is supplied with alternating current as well as with direct current of normal polarity. When the polarized relay is energized in the normal direction and the neutral relay is energized, the associated signal is in condition to indicate "proceed at normal speed" and the line circuit to the rear is supplied with alternating current as well as with direct current of normal polarity. The signaling scheme illustrated in Figs. 1A, 1B, and 1C, therefore, provides a distinctive control for each of four sections in the rear of an occupied section whereby the wayside signals are caused to provide a four-block, five-indication, signal system.

Referring next to Figs. 2A and 2B, the system illustrated herein provides a four-indication, three-block, system of signaling.

Each signal includes an upper unit U and lamp E which functions in a manner identical to that described for the searchlight mechanisms shown in Figs. 1A, 1B, and 1C. Each signal also includes a lower unit LA which is here shown as a single yellow lamp Y.

For controlling the signals, each section is provided with the usual polarized direct current relay H and with the usual neutral direct current relay J. The relays H and J are connected to the associated line circuit in the same manner as described for the system shown in Figs. 1A, 1B, and 1C.

For controlling the lamps E and Y, each section is provided with the usual approach lighting relay ER which is connected, in multiple with the resistor 29, in series with the line circuit for the section next in rear.

Each section is provided with the usual battery 9 and with the usual source of alternating current.

Each section is also provided with the usual transformer N having its primary winding 26 connected to the terminals BX and CX of the source of alternating current energy and having

its secondary winding 27, at times, connected in series with the line circuit for the section next in rear.

The relays H and J control the upper units U and the lower units LA in the following manner: When the relay H is deenergized (see signal 13), both upper and lower units are deenergized so that, when lamp 13E is lighted, the signal will display a single red light to indicate "stop". When the relay H is energized in the reverse direction (see signal 12), operating winding 22 of upper unit U of that signal is energized in the reverse direction by a circuit which passes from terminal B through reverse polar contact 95-96 of relay 12H, operating winding 22, and front contact 97 as well as normal contact 98-99 both of relay 12H to terminal C, so that, when lamp 12E is lighted, the signal will display a single yellow light to indicate "approach next signal prepared to stop". When relay H is energized in the normal direction and relay J is deenergized (see signal 11), operating winding 22 of upper unit U of that signal is energized in the reverse direction over a circuit which passes from terminal B through back point of contact 100 of relay 11J, normal polar contact 101-96 of relay 11H, operating winding 22, front contact 102 of relay 11H, normal polar contact 98-103 of relay 11H, and back point of contact 104 of relay 11J; and a circuit is established for lamp Y of lower unit LA which includes back contact 105 of relay 11J and front contact 106 as well as normal polar contact 107-108 both of relay 11H so that when back contact 28 of relay 11ER becomes closed, the signal will display a yellow light above a yellow light to indicate "approach next signal at medium speed".

When relay H is energized in the normal direction and relay J is energized (see signal 10), operating winding 22 of upper unit U of that signal is energized in the normal direction over a circuit which passes from terminal B through front point of contact 109 of relay 10J, normal polar contact 103-98 as well as front contact 110 both of relay 10H, operating winding 22, normal polar contact 96-101 of relay 12H, and front point of contact 111 of relay 12J so that, when lamp 10E is lighted, the signal will display a single green light to indicate "proceed at normal speed".

As shown in the drawings, the section immediately to the right of location Y is occupied by a train K so that the line circuit for the control of relay 13H and 13J is opened. Consequently, both relays are deenergized.

When relay 13H is deenergized, relay 12H is supplied with energy in the reverse direction over a circuit which passes from terminal B of battery 9 at signal 13, through relay 13ER and resistor 29 in multiple, back point of contact 112 of relay 13H, front contact 113 of relay 6TR, front contact 114 of relay 5TR, operating winding 23, front contact 115 of relay 5TR, front contact 116 of relay 6TR, and back point of contact 117 of relay 13H to terminal C.

When relay 12H is energized in the reverse direction, relay 11H is energized in the normal direction over a circuit which passes from terminal B of battery 9 at signal 12, through relay 12ER and resistor 29 in multiple, front point of contact 118 of relay 12H, front contact 119 of relay 4TR, front contact 120 of relay 3TR, operating winding 23, front contact 121 of relay 3TR, front contact 122 of relay 4TR, front point of

contact 123 of relay 12H, and reverse polar contact 124—125 of relay 12H to terminal C.

When relay 11H is energized in the normal direction, relay 10H is energized in the normal direction over a circuit which passes from terminal B of battery 9 at signal 11, through relay 11ER and resistor 29 in multiple, front point of contact 126 of relay 11H, front contact 127 of relay 2TR, front contact 128 of relay 1TR, operating winding 23, front contact 129 of relay 1TR, front contact 130 of relay 2TR, front point of contact 131 of relay 11H, normal polar contact 124—132 of relay 11H and secondary winding 27 of transformer 11N to terminal C; and primary winding 84 of transformer 10M is energized by a circuit which passes from one terminal of secondary winding 27 of transformer 11N, through battery 9 at signal 11, relay 11ER and resistor 29 in multiple, front point of contact 126 of relay 11H, front contact 127 of relay 2TR, front contact 128 of relay 1TR, resistor 10F, primary winding 84, front contact 129 of relay 1TR, front contact 130 of relay 2TR, front point of contact 131 of relay 11H, and normal polar contact 124—132 of relay 11H to the other terminal of secondary winding 27. When primary winding 84 of transformer 10M is energized, current is induced in secondary winding 27 so that relay 10J is energized by direct current through asymmetric unit 10Q.

When relay 10H is energized in the normal direction, the line circuit for the section immediately in rear of location V is supplied with alternating current simultaneously with direct current of normal polarity so that the signal (not shown) to the rear will be in a condition for displaying the normal proceed indication.

The retained neutral relays H function to prevent tumble-down of the signal control circuits to the rear during pole-changing periods and to prevent momentary improper proceed indications during the passage of high speed light engines from one section to another, in a manner identical to that described for the system shown in Figs. 1A, 1B, and 1C.

To sum up for the system illustrated in Figs. 2A and 2B, each signal is controlled by a polarized direct current relay directly connected to a line circuit and by a neutral relay connected to the line circuit through a transformer and an asymmetric unit. The line circuit is governed by the track relays for the section with which the signal is associated and by the polarized signal control relay of the signal next in advance. When the polarized relay is deenergized, the associated signal is in condition to indicate stop and the line circuit in the rear is supplied with direct current only of reverse polarity. When the polarized relay is energized in the reverse direction, the associated signal is in condition to indicate "approach next signal prepared to stop" and the line circuit in the rear is supplied with direct current only of normal polarity. When the polarized relay is energized in the normal direction and the neutral relay is deenergized, the associated signal is in condition to indicate "approach next signal at medium speed" and the line circuit in the rear is supplied with alternating current as well as with direct current of normal polarity. When the polarized relay is energized in the normal direction and the neutral relay also is energized, the associated signal is in condition to indicate "proceed at normal speed" and the line circuit to the rear is supplied with alternating current as well as with

direct current of normal polarity. The signalling system illustrated in Figs. 2A and 2B, therefore, provides a distinctive control for each of these sections in the rear of an occupied section whereby the wayside signals are caused to provide a three-block, four-indication, signal system.

Referring now to Fig. 3, the reference character A with a prefix the same as the reference character of the associated signal designates an alternator which may be substituted at each signal for the usual source of alternating current the terminals of which were designated in the preceding drawings by the reference characters BX and CX.

As here shown, the alternator A is of the well-known tuned reed type. The reference character 134 designates an elastic reed which is caused to vibrate between terminals 135 and 136 by a control winding 137. In the deenergized condition, reed 134 does not connect with either terminal 135 or 136 but does connect with a terminal 138. When energy is supplied to the alternator A, winding 137 will attract reed 134 causing it to connect with terminal 136 and to move away from terminal 138, causing winding 137 to become deenergized. Upon deenergization of winding 137, the resilience of reed 134 will cause it to move away from terminal 136 and to connect with terminal 135 as well as with terminal 138. The circuit for winding 137 being then again completed through terminal 138, winding 137 will again attract reed 134 causing the cycle of operation just described to be repeatedly energized and deenergized as long as energy is supplied to its control circuit.

When reed 134 connects with terminal 136, current is supplied to the right-hand portion of the primary winding 139 of transformer NA; and when reed 134 connects with terminal 135, current is supplied in the opposite direction to the left-hand portion of primary winding 139. Alternating current, therefore, will be induced in the secondary winding 140 of transformer NA. The secondary winding 140 is connected in series with the line circuit for the section next in rear whenever the relay H is energized in the normal direction in a manner the same as described for secondary winding 27 of transformer N shown in Figs. 2A and 2B.

It will be noted that the operating winding 23 of relay H is not provided with a slow pickup characteristic and that the retaining winding 24 of relay H is not controlled over a front contact of the rear track relay. It is understood, of course, that such control may be provided if it is desired to prevent possible undesirable signal indications under high speed light engine movements. Otherwise, the relay H and the relay J control the associated signal and the line circuit for the section next in rear in exactly the same manner as described for the system shown in Figs. 2A and 2B.

That is, when relay H is deenergized, the associated signal will be in condition to display the "stop" indication and the line circuit in rear will be supplied with direct current only of reverse polarity. When the relay H alone is energized in the reverse direction, the associated signal will be in condition to indicate "prepare to stop at next signal" and the line circuit in rear will be supplied with direct current only of normal polarity. When the relay H alone is energized in the normal direction, the associated signal will be in condition to indicate "approach next signal at medium speed" and the line circuit in rear will be supplied with direct current only of normal polarity. When the relay H alone is energized in the normal direction, the associated signal will be in condition to indicate "approach next signal at medium speed" and the line circuit in rear will

be supplied with alternating current simultaneously with direct current of normal polarity. When the relay H is energized in the normal direction and the relay J also is energized, the associated signal will be in condition to indicate "proceed at normal speed" and the line circuit in rear will be supplied with alternating current simultaneously with direct current of normal polarity.

10 Although I have illustrated only one signal and associated apparatus in Fig. 3, it is understood that any or all signals shown in Figs. 2A and 2B may, if desired, be controlled in a similar manner.

15 Referring now to Fig. 4, I have shown herein circuits and apparatus which may be used when a polarized relay HA of the ordinary type is substituted for the polarized relay H having the retained neutral feature. The slow-releasing repeating relay HP is provided for the control of the line circuit for the section next in rear so that, during pole-changing periods, when the relay HA releases momentarily, the relay HP will maintain its front contacts closed to provide uninterrupted energization of the line circuit to the rear.

20 The relay HP is provided with two pickup circuits. One circuit passes from terminal B through front contact 142 of relay HA, signal contact 143—144 closed when the signal is in the clear indication position and relay HP to terminal C. The other circuit passes from terminal B through front contact 142 of relay HA, signal contact 143—25 145 closed when the signal is in the stop and caution position, signal contact 146—147 closed when the signal is in the caution position, and relay HP to terminal C. That is, relay HP is energized whenever relay HA is energized provided the upper mechanism U of the associated signal is 30 in the clear or caution position.

25 Contacts 148 and 149 of relay HP and normal contact 150—151 and reverse contact 150—152 of relay HA control the current supplied to the line circuit for the section next in rear in a manner similar to that described for the relay HA shown in Figs. 2A and 2B. That is, when the relay HP is deenergized, the line circuit in rear is supplied with direct current only of reverse polarity, and when the relay HP is energized and the relay 35 HA is energized in the reverse direction, the line circuit in rear is supplied with direct current only of normal polarity; whereas when the relay HP is energized and the relay HA is energized in the normal direction, secondary winding 27 of transformer N is connected in series with the line circuit in rear so that alternating current is supplied to such line circuit simultaneously with direct 40 current of normal polarity.

45 The relays HA and J control the associated signal in a manner similar to that described for the relays H and J shown in Figs. 2A and 2B. That is, when the relay HA is deenergized, the signal is in condition to display the stop indication. When the relay HA alone is energized in the reverse direction, the signal is in condition to indicate "approach next signal prepared to stop". When the relay HA alone is energized in the normal direction, the signal is in condition to indicate "approach next signal at medium speed". 55 When the relay HA is energized in the normal direction and the relay J also is energized, the signal is in condition to indicate "proceed at normal speed".

50 It will be noted that operating winding 22 of upper mechanism U is provided with a branch cir-

cuit around front contact 154 of relay H which circuit includes front contact 153 of relay HP. This branch path remains closed during pole-changing periods when front contact 154 of relay HA becomes momentarily opened and thereby 5 reduces the period of time during which winding 22 of mechanism U is without energy since with contact 153 of relay HP closed, the only time involved is the time required for the polar contacts of relay HA to move between their normal 10 and reverse positions. The release time of mechanism U usually will be sufficiently slow to bridge this open circuit period so that the signal does not momentarily assume an improper position.

55 Although I have shown in Fig. 4, only one signal and associated apparatus, it is understood that each signal shown in Figs. 2A and 2B may be controlled in a similar manner if desired.

60 Referring now to Fig. 5, I have illustrated herein a scheme for connecting the secondary winding 27 of transformer N in multiple with the line circuit for the section next in rear instead of in series as illustrated in the preceding figures. As here shown, secondary winding 27 is connected by means of a resistor 158 across the line circuit 25 between the contacts of the relay H and the approach lighting relay ER. The resistor 158 prevents excessive flow of direct current from the battery 9 in the secondary winding 27 and the reactor 159 prevents excessive flow of alternating 30 current through the relay EP and the battery 9. The primary winding 26 of transformer N is connected with the terminals EX and CX of the alternating current source of energy over front contact 155 and normal polar contact 156—157 both 35 of relay H. It will be readily apparent that when relay H is energized in the normal direction, alternating current will be supplied simultaneously with direct current of normal polarity to the line circuit for the section next in rear. It will 40 be apparent also that this modification may be applied to any of the signal systems described in the preceding figures.

45 Although I have herein shown and described several forms of apparatus embodying my invention, it is understood that various changes and modifications may be made therein within the scope of the appended claims without departing from the spirit and scope of my invention.

Having thus described my invention, what I 50 claim is:

1. In combination, a section of railway track, a line circuit for said section, track circuit means for said section for governing said line circuit, means controlled by traffic conditions in advance 55 of said section for supplying said line circuit with direct current only of one polarity or with direct current only of the other polarity or with alternating current simultaneously with direct current of said one polarity, and signaling means for 60 said section controlled by said line circuit and selectively responsive to the character and number of currents with which such line circuit is supplied.

2. In combination, a section of railway track, 65 a line circuit for said section, track circuit means for said section for governing said line circuit, means controlled by traffic conditions in advance of said section for supplying said line circuit with direct current only of one polarity or with direct 70 current only of the other polarity or with alternating current simultaneously with direct current of said one polarity or with alternating current simultaneously with direct current of the other polarity, and signaling means for said 75

section governed by said line circuit and selectively responsive to the character and number of currents with which such line circuit is supplied.

3. In combination, a section of railway track having a track circuit including a track relay, a line circuit for said section including a pair of line wires each including a front contact of said track relay, a polarized direct current line relay connected to said line circuit, a direct current neutral line relay, means including an asymmetric unit for connecting said neutral relay to said line circuit, a signal for said section controlled by said two line relays, and means governed by traffic conditions in advance of said section for supplying said line circuit with direct current only of one polarity or with direct current only of the other polarity or with alternating current simultaneously with direct current of said one polarity.

4. In combination, a section of railway track having a track circuit including a track relay, a line circuit for said section governed by the associated track relay, means governed by traffic conditions in advance of said section for supplying said line circuit with direct current only or with alternating current simultaneously with direct current, a direct current line relay connected to said line circuit, another direct current line relay receiving energy from said line circuit through an asymmetric unit, and a signal for said section governed by said two line relays.

5. In combination, a section of railway track having a track circuit including a track relay, a line circuit for said section governed by the associated track relay, means governed by traffic conditions in advance of said section for supplying said line circuit with direct current only or with alternating current simultaneously with direct current, a direct current line relay connected to said line circuit, another direct current line relay receiving energy from said line circuit through an asymmetric unit, and a signal for said section capable of displaying several distinctive aspects having varying degrees of speed restrictions and governed by said two line relays in such a manner that said signal will display its least restrictive aspect only if said two line relays are energized simultaneously.

6. In combination, a section of railway track having a track circuit including a track relay, a line circuit for said section including a pair of line wires each including a front contact of said track relay, a polarized direct current line relay connected to said line circuit, a direct current neutral line relay, means including an asymmetric unit for connecting said neutral relay to said line circuit, means governed by traffic conditions in advance of said section for supplying said line circuit with direct current only of one polarity or with direct current only of the other polarity or with alternating current simultaneously with direct current of said one polarity or with alternating current simultaneously with direct current of said other polarity, and a signal for said section capable of displaying several distinctive aspects having varying degrees of speed restrictions and governed by said two line relays in such a manner that said signal will display its two least restrictive aspects only if said two line relays are energized simultaneously.

7. In combination, a section of railway track having a source of current connected across the rails at one end of the section and a track relay connected across the rails at the other end of the section, a line circuit for said section including a pair of line wires each governed by a front con-

tact of the associated track relay, a direct current relay connected to said line circuit, another direct current relay, means including an asymmetric unit and a transformer as well as a resistor for connecting said other relay to said line circuit, means governed by traffic conditions in advance of said section for supplying said line circuit with direct current only or with alternating current simultaneously with direct current, and a signal for said section governed by said two direct current relays.

8. A railway signal system comprising a stretch of railway track divided into a plurality of successive sections, a line circuit for each section each including a pair of line wires, track circuit means for each section for governing the associated line circuit, a direct current polarized line relay for each section connected to the associated line circuit, a direct current neutral line relay for each section receiving energy from the associated line circuit through an asymmetric unit, a source of direct current energy for each section, means for each section governed by the associated polarized line relay for supplying the line circuit for the section next in rear with current of one polarity or the other polarity from the associated source of direct current according as said polarized line relay is energized or deenergized respectively, a source of alternating current energy for each section, a transformer for each section having a primary winding and a secondary winding, said primary winding connected to its associated source of alternating current, means for each section for connecting the secondary of the associated transformer in series with said line circuit next in rear effective when the associated polarized relay is energized by current of said one polarity, and traffic governing means for each section controlled by both the associated line relays.

9. A railway signal system comprising a stretch of railway track divided into a plurality of successive sections, a line circuit for each section each including a pair of line wires, track circuit means for each section for governing the associated line circuit, a direct current polarized line relay for each section connected to the associated line circuit, a direct current neutral line relay for each section receiving energy from the associated line circuit through an asymmetric unit, a source of direct current energy for each section, means for each section governed by the associated polarized line relay for supplying the line circuit for the section next in rear with current of one polarity or with current of the other polarity from the associated source of direct current according as said polarized line relay is energized or deenergized respectively, a source of alternating current energy for each section, a transformer for each section having a primary winding and a secondary winding, said secondary winding connected in multiple with the associated source of direct current, means for each section for connecting the primary winding of the associated transformer to the associated source of alternating current effective when the associated polarized relay is energized by current of said one polarity, and traffic governing means for each section controlled by the two associated line relays.

10. A railway signal system comprising a stretch of railway track divided into a plurality of successive sections, a line circuit for each section each including a pair of line wires, track circuit means for each section for governing the associated line circuit, a direct current polarized line

- relay for each section connected to the associated line circuit, a direct current neutral line relay for each section receiving energy from the associated line circuit through an asymmetric unit, a source of direct current energy for each section, means for each section governed by the associated polarized line relay for supplying the line circuit for the section next in rear with current of one polarity or with current of the other polarity from the associated source of direct current according as said polarized line relay is energized or deenergized respectively, a source of alternating current energy for each section, a transformer for each section having a primary winding and a secondary winding, said primary winding connected to the associated source of alternating current, means for each section including a front neutral contact of the associated polarized relay and a polar contact closed when such relay is energized by current of said one polarity for connecting the secondary of the associated transformer in series with said line circuit next in rear, and traffic governing means for each section controlled by said two associated line relays.
11. In combination, a plurality of successive sections of railway track, a line circuit for each section each including a pair of line wires, track circuit means for each section for governing the associated line circuit, a direct current polarized line relay for each section connected to the associated line circuit, a direct current neutral line relay for each section receiving energy from the associated section through an asymmetric unit, means for each section for supplying direct current only of normal or of reverse polarity to the line circuit for the section next in rear according as the associated polarized relay is energized or deenergized respectively, means for each section for supplying alternating current simultaneously with direct current of normal polarity to such line circuit next in rear when the associated polarized relay is energized by current of normal polarity, an auxiliary relay for each section connected in series with such line circuit next in rear, and a signal for each section controlled by said two associated relays and said associated auxiliary relay.
12. In combination, a plurality of successive sections of railway track, a line circuit for each section each including a pair of line wires, track circuit means for each section for governing the associated line circuit, a direct current polarized line relay for each section connected to the associated line circuit, a direct current neutral line relay for each section receiving energy from the associated section through an asymmetric unit, means for each section for supplying direct current only of normal or of reverse polarity to the line circuit for the section next in rear according as the associated polarized relay is energized or deenergized respectively, means for each section for supplying alternating current simultaneously with direct current of normal polarity to such line circuit next in rear when the associated polarized relay is energized by current of normal polarity, an auxiliary relay for each section connected in series with such line circuit next in rear, a resistor connected around each said auxiliary relay, and a signal for each section controlled by said two associated line relays and by said associated auxiliary relay.
13. In combination, a plurality of successive sections of railway track, a line circuit for each section each including a pair of line wires, track circuit means for each section for governing the

associated line circuit, a direct current polarized line relay for each section connected to the associated line circuit, a direct current neutral line relay for each section receiving energy from the associated section through an asymmetric unit, means for each section for supplying direct current only of normal or of reverse polarity to the line circuit for the section next in rear according as the associated polarized relay is energized or deenergized respectively, means for each section for supplying alternating current simultaneously with direct current of normal polarity to such line circuit next in rear when the associated polarized relay is energized by current of normal polarity, an approach lighting relay for each section connected in series with such line circuit in rear, a signal for each section governed by said two associated line relays, and a lamp for each signal governed by the associated approach lighting relay.

14. In combination, a plurality of successive sections of railway track, a line circuit for each section each including a pair of line wires, track circuit means for each section for governing the associated line circuit, a direct current polarized line relay for each section connected to the associated line circuit, a direct current neutral line relay for each section receiving energy from the associated section through an asymmetric unit, means for each section for supplying direct current only of normal or of reverse polarity to the line circuit for the section next in rear according as the associated polarized relay is energized or deenergized respectively, means for each section for supplying alternating current simultaneously with direct current of normal polarity to such line circuit next in rear when the associated polarized relay is energized by current of normal polarity, an approach lighting relay for each section connected in series with such line circuit next in rear, and a signal mechanism including a lamp for each section, said signal mechanism controlled by contacts of said two associated line relays and said lamp controlled by a contact of said associated approach lighting relay.

15. A railway signaling system comprising a plurality of successive sections of railway track, a line circuit for each section, track circuit means for each section for governing the associated line circuit, a first direct current line relay for each section connected to the associated line circuit, a second direct current line relay for each section, means including an asymmetric unit for connecting said second relay to the associated line circuit, means governed by traffic conditions in advance of said section for supplying the line circuit for the section next in rear with direct current only or with alternating current simultaneously with direct current, an approach lighting relay for each section connected in series with such line circuit next in rear, and a signal for each section governed by said two associated line relays as well as by the associated approach lighting relay.

16. In a signaling system for a railway track divided into sections, a polarized direct current relay for each section having polar and neutral contacts, a neutral direct current relay for each section connected to an asymmetric unit, signals for each section controlled by neutral and polar contacts of the associated polarized relay and by contacts of the associated neutral relay, means for each section including neutral and polar contacts of the associated polarized relay for supplying di-

- rect current only of normal or reverse polarity to the corresponding polarized relay of the section next in rear according as said first mentioned relay is energized or deenergized respectively and 5 for supplying alternating current to the asymmetric unit associated with the neutral relay of the section next in rear when said first mentioned polarized relay is energized in the normal direction, means for each polarized relay effective 10 10 for normally rendering the neutral contacts of such polarized relay slow acting, track circuit means for each section for controlling the associated polarized and neutral relays and for at times disabling the slow-acting means of the associated polarized relay. 15
17. In a signaling system for a railway track divided into sections, a polarized direct current relay for each section having polar and neutral contacts, a neutral direct current relay for each 20 section connected to an asymmetric unit, signals for each section controlled by neutral and polar contacts of the associated polarized relay and by contacts of the associated neutral relay, means for each section including neutral and 25 polar contacts of the associated polarized relay for supplying direct current only of normal or reverse polarity to the corresponding polarized relay of the section next in rear according as said first mentioned relay is energized or deenergized respectively, and for supplying alternating current to the asymmetric unit associated with the neutral relay of the section next in rear when said first mentioned polarized relay is energized in the normal direction, means for each 30 35 polarized relay effective for normally rendering the neutral contacts of such polarized relay slow acting, track circuit means for each section including a forward track relay and a rear track relay, means for each section including 40 both the forward and the rear track relays for controlling the associated polarized and neutral relays, and means for each section including the rear track relay of such section for disabling the slow-acting means of the associated polarized 45 relay when said rear track relay is released.
18. In a signaling system for a railway track divided into sections, a polarized direct current relay for each section having polar and neutral contacts, a neutral direct current relay for each 50 section connected to an asymmetric unit, signals for each section controlled by neutral and polar contacts of the associated polarized relay and by contacts of the associated neutral relay, means for each section including neutral and polar 55 contacts of the associated polarized relay for supplying direct current only of normal or reverse polarity to the corresponding polarized relay of the section next in rear according as said first mentioned relay is energized or deenergized respectively and for supplying alternating current to the asymmetric unit associated with the neutral relay of the section next in rear when said first mentioned polarized relay is energized in the normal direction, means for each polarized relay effective for normally rendering the neutral contacts of such polarized relay slow acting, track circuit means for each section including a forward track relay and a rear track relay, means for each section including both the 60 forward and the rear track relays for controlling the associated polarized and neutral relays, and means for each section including a front contact of the rear track relay associated therewith for rendering said slow-acting means of the associated polarized relay ineffective. 65

19. In combination, a section of railway track having a track circuit including a track relay, a line circuit for said section including a front contact of said track relay, means governed by traffic conditions in advance of said section for supplying said line circuit with direct current only of normal polarity or with direct current only of reverse polarity or with alternating current simultaneously with direct current of normal polarity or with alternating current simultaneously with direct current of reverse polarity, a direct current polarized line relay connected to said line circuit, a direct current neutral line relay, means including an asymmetric unit for connecting said neutral relay to said line circuit, and a signal for said section controlled by neutral and polar contacts of said polarized relay and by contacts of said neutral relay. 15
20. In combination, a section of railway track having a track circuit including a track relay, a line circuit for said section including a front contact of said track relay, means governed by traffic conditions in advance of said section for supplying said line circuit with direct current only of normal polarity or with direct current only of reverse polarity or with alternating current simultaneously with direct current of normal polarity or with alternating current simultaneously with direct current of reverse polarity, a direct current polarized line relay connected to said line circuit, a direct current neutral line relay, means including an asymmetric unit for connecting said neutral relay to said line circuit, a signal for said section including a first mechanism and a second mechanism each selectively responsive to the polarity of the current supplied thereto, and means including contacts of both line relays for reversibly governing both said mechanisms. 25 30 35
21. In combination, a section of railway track having a track circuit including a track relay, a line circuit for said section including a front contact of said track relay, means governed by traffic conditions in advance of said section for supplying said line circuit with direct current only of normal polarity or with direct current only of reverse polarity or with alternating current simultaneously with direct current of normal polarity or with alternating current simultaneously with direct current of reverse polarity, a direct current polarized line relay connected to said line circuit, a direct current neutral line relay, means including an asymmetric unit for connecting said neutral relay to said circuit, a signal for said section including a first mechanism and 40 45 50 55 a second mechanism, a first circuit for said first mechanism including a pair of front contacts of said neutral relay and a pair of normal polar contacts of said polarized relay as well as a front contact of said polarized relay, a second circuit for said first mechanism including a pair of front contacts of said neutral relay and a pair of reverse polar contacts of said polarized relay as well as a front neutral contact of said polarized relay, a third circuit for said first mechanism including a pair of back contacts of said neutral relay and a pair of normal polar contacts of said polarized relay as well as a front contact of said polarized relay, a fourth circuit for said first mechanism including a pair of back contacts of said neutral relay and a pair of reverse polar contacts of said polarized relay as well as a front contact of said polarized relay, a first circuit for said second mechanism including a pair of front contacts of said neutral relay and a front contact of said 60 65 70 75

polarized relay, and a second circuit for said second mechanism including a pair of back contacts of said neutral relay and a normal polar contact as well as a front neutral contact of said polarized relay.

22. In combination, a section of railway track having a track circuit including a track relay, a line circuit for said section including a front contact of said track relay, means governed by traffic conditions in advance of said section for supplying said line circuit with direct current only of normal polarity or with direct current only of reverse polarity or with alternating current simultaneously with direct current of normal polarity or with alternating current simultaneously with direct current of reverse polarity, a direct current polarized line relay connected to said line circuit, a direct current neutral line relay, means including an asymmetric unit for connecting said neutral relay to said line circuit, and a signal for said section controlled by said two line relays and arranged to have a first aspect when said polarized relay is deenergized, a second aspect when said neutral relay is deenergized and said polarized relay is energized reverse, a third aspect when said neutral relay is deenergized and said polarized relay is energized normal, a fourth aspect when said neutral relay is energized and said polarized relay is energized reverse, and a fifth aspect when said neutral relay is energized and said polarized relay is energized normal.

23. In combination, a section of railway track having a track circuit including a track relay, a line circuit for said section including a front contact of said track relay, means governed by traffic conditions in advance of said section for supplying said line circuit with direct current only of normal polarity or with direct current only of reverse polarity or with alternating current simultaneously with direct current of said one polarity, a direct current polarized line relay connected to said line circuit, a direct current neutral relay, means including an asymmetric unit for connecting said neutral relay to said line circuit, a signal for said section including a first indication unit comprising a mechanism and a second indication unit comprising a lamp, a first circuit for said mechanism including a front contact and a normal polar contact of said polarized relay as well as a front contact of said neutral relay, a second circuit for said mechanism including a front contact and a normal polar contact of said polarized relay as well as a back contact of said neutral relay, a third circuit for said mechanism including a front contact and a reverse polar contact of said polarized relay as well as a back contact of said neutral relay, and a circuit for said lamp including a front contact and a normal polar contact of said polarized relay as well as a back contact of said neutral relay.

24. In combination, a section of railway track having a track circuit including a track relay, a line circuit for said section including a front contact of said track relay, means governed by traffic conditions in advance of said section for supplying said line circuit with direct current only of normal polarity or with direct current only of reverse polarity or with alternating current simultaneously with direct current of normal polarity, a direct current polarized line relay connected to said line circuit, a direct current neutral relay, means including an asymmetric unit for connecting said neutral relay to said line circuit, a signal for said section including a first indication unit comprising a mechanism and a second

indication unit comprising a lamp, contacts operably governed by said signal, a slow-acting repeating relay governed by said contacts and by said polarized relay, energizing circuits for said mechanism and said lamp including contacts of both said polarized and said neutral relays, and a branch circuit for said mechanism including a contact of said repeating relay.

25. A railway signal system comprising a plurality of successive sections of railway track each having a track circuit including a track relay, a line circuit for each section governed by the associated track relay, a polarized direct current relay for each section connected to the associated line circuit, a neutral direct current relay for each section, means including an asymmetric unit for connecting each neutral relay to the associated line circuit, a signal for each section governed by the associated polarized relay and by the associated neutral relay, contacts for each section operably governed by the associated signal, a repeating relay for each section governed by the associated contacts and by the associated polarized relay, means for each section for supplying the line circuit for the section next in rear with direct current only of reverse polarity when said repeating relay is deenergized and for supplying such rear line circuit with direct current only of normal polarity when said repeating relay is energized and said polarized relay is energized reverse as well as for supplying such rear line circuit with alternating current simultaneously with direct current of normal polarity when said repeating relay is energized and said polarized relay is energized normal.

26. A railway signal system comprising a plurality of successive sections of railway track each having a track circuit including a track relay, a line circuit for each section governed by the associated track relay, a polarized direct current relay for each section connected to the associated line circuit, a neutral direct current relay for each section, means including an asymmetric unit for connecting each neutral relay to the associated line circuit, a signal for each section governed by the associated polarized relay and by the associated neutral relay, contacts for each section operably governed by the associated signal, means for each section including a back contact of said polarized relay for supplying direct current only of reverse polarity to the line circuit for the section next in rear, means for each section including a front contact and a reverse polar contact of said polarized relay for supplying direct current only of normal polarity to such rear line circuit, and means for each section including a front contact and a normal polar contact of said polarized relay for supplying alternating current simultaneously with direct current of normal polarity to such rear line circuit.

27. A railway signal system comprising a plurality of successive sections of railway track each having a track circuit including a track relay, a line circuit for each section governed by the associated track relay, a polarized direct current relay for each section connected to the associated line circuit, a neutral direct current relay for each section, means including an asymmetric unit for connecting each neutral relay to the associated line circuit, a signal for each section governed by the associated polarized relay and by the associated neutral relay, contacts for each section operably governed by the associated signal, means for each section including a back contact of said polarized relay for supplying direct

current only of reverse polarity to the line circuit for the section next in rear, means including a front contact and a reverse polar contact of said polarized relay as well as a back contact of said neutral relay for supplying such rear line circuit with direct current only of normal polarity, means including a front contact and a normal polar contact of said polarized relay as well as a back contact of said neutral relay for supplying alternating current simultaneously with direct current of reverse polarity to such rear line circuit, and means including a front contact of said polarized relay and a front contact of said neutral relay for supplying alternating current simultaneously with direct current of normal polarity to such rear line circuit.

28. A railway signal system comprising; a first, a second, a third, and a fourth track section over which traffic normally progresses in the order named, a line circuit for each section including a pair of line wires, track circuit means for each section for governing the associated line circuit, a polarized direct current relay for each section connected to the associated line circuit, a neutral direct current relay for each section receiving energy from the associated line circuit through an asymmetric unit, a signal for each section governed by the associated polarized and neutral relays, means effective when the fourth section is occupied to supply the line circuit for the third section with direct current only of reverse polarity, means then effective to supply the line circuit for the second section with direct current only of normal polarity, and means then effective to supply the line circuit for the first section with alternating current simultaneously with direct current of normal polarity.

29. A railway signal system comprising a first, a second, a third, a fourth, and a fifth track section over which traffic normally progresses in the order named, a line circuit for each section including a pair of line wires, track circuit means for each section for governing the associated line circuit, a polarized direct current relay for each section connected to the associated line circuit, a neutral direct current relay for each section receiving energy from the associated line circuit through an asymmetric unit, a signal for each section governed jointly by the associated polarized and neutral relays, means effective when the fifth section is occupied to supply the line circuit for the fourth section with direct current only of reverse polarity, means then effective to supply the line circuit for the third section with direct current only of normal polarity, means then effective to supply the line circuit for the second section with alternating current simultaneously with direct current of reverse polarity, and means then effective to supply the line circuit for the first section with alternating current simultaneously with direct current of normal polarity.

30. A railway signal system comprising a plurality of successive sections of railway track each having a track circuit including a track relay, a line circuit for each section governed by the associated track relay, means effective when one section is occupied to supply the line circuit for the section first in rear of such occupied section with current of one character, means then effective to supply the line circuit for the section second in rear of such occupied section with current of another character, means then effective to supply the line circuit for the section third in

rear of such occupied section with current of still a different character simultaneously with current of said other character, and signaling means for each section governed by the associated line circuit and selectively responsive to the character and number of the currents with which such line circuit is supplied.

31. A railway signal system comprising a plurality of successive sections of railway track each having a track circuit including a track relay, a line circuit for each section governed by the associated track relay, means effective when one section is occupied to supply the line circuit for the section first in rear of such occupied section with current of one character, means then effective to supply the line circuit for the section second in rear of such occupied section with current of another character, means then effective to supply the line circuit for the section third in rear of such occupied section with current of still a different character simultaneously with current of said other character, means then effective to supply the line circuit for the section fourth in rear of such occupied section with said current of a different character as well as with current of said one character, and signaling means for each section governed by the associated line circuit and selectively responsive to the character and number of the currents with which such line circuit is supplied.

32. In combination, a section of railway track having a track circuit including a track relay, a line circuit for said section including a pair of line wires each including a front contact of said track relay, a polarized direct current line relay connected to said line circuit, a direct current neutral line relay, means including an asymmetric unit for connecting said neutral relay to said line circuit, a signal for said section controlled by said two line relays, and means including an alternator and governed by traffic conditions in advance of said section for supplying said line circuit with direct current only of one polarity or with direct current only of the other polarity or with alternating current simultaneously with direct current of said one polarity or with alternating current simultaneously with direct current of said other polarity.

33. A railway signal system comprising a stretch of railway track divided into a plurality of successive sections, a line circuit for each section including a pair of line wires, track circuit means for each section for governing the associated line circuit, a direct current polarized line relay for each section connected to the associated line circuit, a direct current neutral relay for each section receiving energy from the associated line circuit through an asymmetric unit, a source of direct current energy for each section, means for each section for supplying the line circuit for the section next in rear with current of one polarity or with current of the other polarity from the associated source of direct current according as the associated polarized relay is energized or deenergized respectively, a source of alternating current including a tuned reed alternator for each section, means for each section for supplying said line circuit next in rear with alternating current effective when the associated polarized relay is energized by current of said one polarity, and traffic governing means for each section governed by the two associated line relays.
